UNITED STATES PATENT OFFICE.

MARTIN L. WILLIAMS, OF SOUTH BEND, INDIANA, ASSIGNOR, BY MESNE ASSIGNMENTS,
TO AMERICAN SLEEVE-VALVE MOTOR COMPANY, A CORPORATION OF DELAWARE.

ENGINE.

1,323,210.

Specification of Letters Patent. Patented Nov. 25, 1919.

Application filed April 18, 1913, Serial No. 761,930. Renewed October 17, 1919. Serial No. 331,494.

To all whom it may concern:

Be it known that I, MARTIN L. WILLIAMS, a citizen of the United States, residing in the city of South Bend, county of St. Joseph, and State of Indiana, have invented certain new and useful Improvements in Engines, of which the following is a specification.

This invention relates to improvements in engines and refers more particularly to a four cycle gas engine of the single rotary valve type.

The object of the invention is to provide a novel type of rotary sleeve in combination with the split sealing ring.

The invention consists in the matters hereinafter described and more particularly pointed out in the appended claims.

In the drawings—

20 Figure 1 is a transverse vertical sectional view of an engine embodying my invention;

Fig. 2 is a fragmentary vertical sectional view showing a modified manner of arranging the rotary valve sleeve relative to the 25 piston.

Fig. 3 is a side elevation of the rotary valve sleeve.

Fig. 4 is a bottom view of the sleeve shown in Fig. 3;

30 Fig. 5 is a sectional view taken on lines 5-5 of Fig. 3 and looking in the direction of the arrows;

Fig. 6 is a sectional view taken on lines 6-6 of Fig. 3 and looking in the direction 35 of the arrows;

Fig. 7 is a transverse vertical sectional view of the worm wheel;

Fig. 8 is a top plan view of the wheel shown in Fig. 7;

40 Fig. 9 is a top plan view of the stationary port ring;

Fig. 10 is a vertical sectional view of the same taken on lines 10-10 of Fig. 9, and showing also the expansion ring;

45 Fig. 11 is a plan view of the expansion ring which fits within the port ring;

Fig. 12 is a side elevation of said expansion ring.

Referring to the drawings—

50 1 designates as a whole a crank case, and 2 the crank shaft. The lower end of the crank case serves as an oil pan 7 provided with oil troughs 8. At the upper ends, the crank casing is provided with a cylinder

base 9 on which is supported the engine cylinders, only one cylinder 10 being shown in the vertical section illustrated in Fig. 1.

The piston 11 is connected by piston rod 13 to the crank 2 in any well known manner. Between the cylinder 10 and piston 11 60 is interposed a rotary valve sleeve 12 open at both ends and extending the full length of the cylinder. To the lower end of each rotary valve sleeve 12 is secured a worm wheel 14. Within the upper end of the cylinder 65 is seated a detachable cylinder head 15, the lower end of which fits within the valve sleeve 12. The cylinder head is bolted or otherwise rigidly secured to the cylinder. Between the sleeve wall and the cylinder 70 head is interposed a stationary port ring 16, shown more clearly in detail in Figs. 9 and 10. This ring is provided with six circumferentially spaced ports 17 which register with the inlet and exhaust ports at the upper 75 end of the cylinder walls, hereinafter described. The ported ring is locked against rotation by means of a pin 18 extending into the cylinder head. The ring is also split, as shown at 19 and 20, the split portions of the 80 ring being offset and the ring being split through two oppositely disposed ports, as shown more clearly in Fig. 10. The ring is normally forced outwardly by a spring split collar 21 which rests upon a shoulder 22 85 formed in the lower end of the cylinder head and is provided at its upper face with a conical or tapered portion 23 projecting into a flaring portion 24 formed in the lower end of the port ring 16. The arrangement is 90 such that the collar 21 normally tends to spread the port ring 16 so as to form a gas tight fit between the latter member and the rotary valve sleeve 12, while at the same time allowing the valve sleeve to rotate without undue friction. The central portion of the ported ring 16 i. e., that portion of the ring wall opposite the ports, is counter-bored as shown at 25 in order to insure of effecting 95 expansion, and contraction of the ring. As 100 the valve sleeve 12 rotates about the ported ring 16 in a clockwise direction, the ring, which is held stationary by the pin 18, will thereby be contracted. The object desired is to have the rotation of the sleeve tend to 105 contract the ported ring 16 against the action of the collar 21. This insures more efficient lubrication and the parts are less

liable to score should they run light on oil, for the reason that the more the ring contracts, due to friction of the sleeve, the greater will be the oil space between the 5 ring and the sleeve.

- Referring now to the ports in the cylinder wall, in the upper end of the latter are cast circumferentially extending inlet ports and alternately disposed exhaust ports. Because, 10 however, it is more or less difficult to accurately cast ports, I provide the cylinder with a stationary bushing 28 which is ported as shown at 29 to correspond with the inlet and exhaust ports of the cylinder wall proper. 15 The ports in this bushing may be milled out with absolute accuracy that allows of a micrometer adjustment. The upper end of the cylinder wall is counterbored as shown more clearly in Fig. 1 to receive the bushing, the 20 lower end of the latter resting on a shoulder 30 in the cylinder. The inlet manifold 34 and exhaust manifold 36 lie side by side and are preferably cast integrally, the object being that the exhaust gases passing out of the 25 manifold will more or less heat the inlet gases passing through the inlet manifold. The exhaust ports at the top of the cylinder exhaust into the manifold 36 by means of the vertically extending exhaust conduit 42. 30 Referring now to the ports in the rotary valve sleeve, the latter is provided at its upper end with, in the present instance, three circumferentially extending ports 43, which are of the same size and shape as the inlet 35 and exhaust ports in the cylinder wall, and are spaced one hundred and twenty degrees apart. It will be understood that the ports in the upper end of the sleeve are equal in number to one-half the combined 40 number of the inlet and exhaust ports in the upper end of the cylinder, and each port alternately registers with an inlet and exhaust port in the cylinder as the sleeve rotates. At its lower end the valve sleeve is 45 provided with three circumferentially extending equi-spaced ports 44 adapted to register with the three exhaust ports in the lower end of the cylinder. The sleeve is confined against vertical movement in the cylinder by a flange 45 which lies between the lower end of the cylinder and the upper face of the base but in such a way as not to interfere with the free rotation of the sleeve. The upper end of the sleeve projects into 50 the space between the bushing and the stationary port ring heretofore referred to.

The flange 45 on the lower end of the sleeve is provided with three circumferentially spaced notched portions 104 adapted 60 to register with the locking dogs 105 carried by a worm wheel 106. The worm 107 of the worm wheel 106 intermeshes with the worm wheel 98 and is thus driven by the rotation of the worm shaft. Preferably, the lower 65 ends of the worm wheel 106 are provided

with a plurality of oil ducts 108. By reference to Fig. 1 it will be seen that the worm wheel is inclosed in the supplemental oil chamber. Inasmuch as the various ports in the rotary valve sleeve are all spaced equidistant apart, and the locking recess 104 and locking dogs 105 are similarly spaced, the sleeve must of necessity be fitted in proper position.

In Fig. 2 I have shown a somewhat modified form of construction. This modification consists in providing the head with a sleeve-like extension 109 which extends full length of the cylinder wall and is interposed between the outer wall of the piston 11 and the rotating sleeve 12. This modified form of construction by separating the piston from the sleeve obviates the possibility of the rotation of the sleeve interfering with the reciprocation of the piston, or vice versa.

Let it be assumed that Fig. 1, is a vertical section through one of the cylinders of a four-cylinder four-cycle engine of the type shown in Patent No. 1,268,522 granted to another and myself. As the piston starts down on the first intake stroke the ports in the upper end of the sleeve register with the inlet ports in the upper end of the cylinder, and the supply of gas rushes into the cylinder. At this time the exhaust ports at the upper end of the cylinder are closed by the rotary valve sleeve, and at the lower end of the cylinder are closed by both the sleeve and the cylinder. As the piston descends on the intake stroke, it draws in the gas by vacuum. As the piston reaches the end of its intake stroke, all the inlet and exhaust ports are closed. As the piston starts up on the compression stroke, the ports remain closed until the piston reaches the end of the compression stroke. At the beginning of the power stroke the ports are all closed, and remain closed during said stroke. As the piston reaches the end of the power stroke, the sleeve has rotated so that its lower ports register with the exhaust ports in the lower end of the cylinder. As the piston uncovers the exhaust ports at the lower end the consumed gases escape into the exhaust manifold. The exhaust ports at the upper end of the cylinder are now open while the inlet ports remain closed, and these upper exhaust ports remain closed while the piston is completing its fourth or scavenging stroke.

The invention is not limited to the details of construction shown except as set forth in the appended claims.

I claim as my invention:

1. In a gas engine the combination with a cylinder, and piston therein, of a cylinder head having a split port ring, a ported valve sleeve projecting between the cylinder wall and port ring.

2. In a gas engine, the combination with a cylinder and piston therein of a cylinder

- head having a split port ring, a ported valve sleeve projecting between the cylinder wall and port ring, and means whereby rotation of said sleeve tends to contract said ring.
- 5 3. In a gas engine, the combination with a ported cylinder and piston therein, of a cylinder head, a split port ring projecting from the head into the cylinder, a spring member tending to force the split portions of the
- 10 ring apart, a ported rotary valve sleeve extending between the port ring and cylinder wall, and means whereby rotation of the
- sleeve tends to open said ring against the action of said spring member.
4. In a gas engine, the combination with a cylinder, of a rotary sleeve mounted therein, and adapted to rotate, a split sealing ring mounted within said sleeve and adapted to contract upon the rotation of the sleeve.

MARTIN L. WILLIAMS.
